[57] CLAIM

The ornamental design for a combination beach towel and chair, as shown and described.

DESCRIPTION

FIG. 1 is a top plan view of a combination beach towel and chair showing my new design;
FIG. 2 is a bottom plan view thereof;
FIG. 3 is a folded side elevational view thereof, the opposite side being a mirror image of that shown;
FIG. 4 is an unfolded side elevational view thereof; the opposite side being a mirror image of that shown; and
FIG. 5 is a perspective view thereof, shown folded into its configuration as a chair.

FIG. 1

FIG. 2

FIG. 3

FIG. 4

FIG. 5
